UNITED STATES PATENT OFFICE.

EUGENE ROBERTS, OF SALT LAKE CITY, UTAH, ASSIGNOR TO THE WESTERN STATES MACHINE COMPANY, OF SALT LAKE CITY, UTAH, A CORPORATION OF UTAH.

MOUNT FOR DRIVING CENTRIFUGAL MACHINES.

Application filed September 19, 1919. Serial No. 324,928.

To all whom it may concern:

Be it known that I, EUGENE ROBERTS, a citizen of the United States, and resident of Salt Lake City, in the county of Salt Lake and State of Utah, have invented certain new and useful Improvements in a Mount for Driving Centrifugal Machines, of which the following is a specification.

This invention relates to the mounting and driving of centrifugal machines and is intended to provide a simple and efficient construction by which a centrifugal of the suspended gyratory type may be driven by direct connections leading to the line shaft or other driving means while permitting the requisite degree of oscillation or gyration when the centrifugal is rotating.

Generally speaking the invention consists in the combination of a gyratory basket shaft suspended at its upper end on a universal joint with an overhead axially aligned non-oscillatory driving shaft which carries centrifugally operating clutch blocks arranged to form a frictional driving engagement with an annular member secured to the basket shaft preferably at approximately the level of the center of oscillation of the basket shaft, and means operable at will to force the centrifugally actuated blocks out of frictional engagement with said annular member while the machine is rotating.

This and other features of the invention will be more particularly described in the following specification and will be defined in the claims hereto annexed.

In the accompanying drawings I have illustrated a preferred form embodying the principles of this invention in which—

Figure 1 is an assembled view showing chiefly in sectional elevation the arrangement of the driving shaft, the centrifugal basket shaft and the intermittent controllable driving connection by which the basket shaft is driven without interfering with its proper oscillation.

Figure 2 is a detail showing a plan view of the spider and pivotal arms by which the clutch blocks are controlled.

Figure 3 is a detail showing a side elevation at one of the clutch block arms and its connection with the clutch block.

In order to secure good results in practice it is important to have a driving mechanism that will act effectively to quickly bring the

machine up to normal speed of operation and which shall be so arranged with reference to the oscillatory basket shaft as not to interfere with the oscillation of the shaft by which the machine balances itself and to avoid bringing lateral pressure against the rotary bearings which rotatively support the basket shaft in its oscillatory suspension head.

In the practice of the invention according to the form illustrated the centrifugal and its driving mount are preferably secured to the upper and lower I-beams *a* running along the side of the mixer. On the lower I-beam is mounted an inverted hanger *a'* inside of which are placed suitable annular elastic buffers or rings *a''* between which is located the annular flange *b'* of the oscillatory bearing head *b*, which flange has a peripheral contact with the inside wall of the hanger to prevent lateral shifting. The convex curvature of the outer surface of the flange permits oscillation of the bearing or suspension head and this peripheral curvature is concentric to the center of oscillation. A compression ring *a''* is mounted above the upper buffer and pressure is applied by means of the hollow nut *a''* which has a screw thread engagement with the upper end of the hanger to secure the requisite compression of the buffer rings.

The oscillatory bearing head held between these two compressible buffers is not only permitted to have a gyratory movement on a universal joint as it were, but the buffers themselves act to afford a yielding resistance to said gyratory movement.

Inside the bearing head are provided upper and lower anti-friction bearings of suitable type, in this case the roller type of bearing being used, as shown at *c* to afford an elongated rotary bearing support for the gyratory basket shaft *d* which carries the basket *d''* at its lower end in the usual manner. Lubrication is provided by means of a stationary oil duct or pipe *d'* whose lower end acts as a scoop to receive the oil inside the oil cup *d''* secured to the shaft *d*, the upper end of said duct discharging inside the bearing head above the upper bearing. It will be understood that the head *b* has a gyratory or oscillatory movement about an axial center level with the flange *b'* intermediate of its ends but does not rotate.

To the upper end of the basket shaft *d* is securely attached an annular driving member which is in the form of a pulley *e* having an outward upturned annular flange *e'* extending concentrically around the shaft and leaving an annular trough between itself and the main body of the pulley.

The driving shaft *o* is mounted in fixed bearings *m'* *m''* carried by the bracket *m* which is secured to the upper I-beam *a*. This driving shaft *o* may be driven by any suitable application of power, but in this case it is driven by a bevelled gear connection *o'* leading from the horizontal line shaft *r* which line shaft is carried in suitable bearings in the bracket *m*.

To the lower end of the driving shaft *o* which is axially aligned with the central axis of the basket shaft is a dome-like spider *s* provided with pairs of lugs or ears *s'* on opposite sides of the center which carry horizontal pivot bolts *s'* on which are mounted pivoted arms or levers *s''*. Levers *s''* are provided at their lower ends with ball bearings *s'''* which are seated loosely in interior sockets formed in segmental clutch blocks *s'''* whose outer and inner faces are curved to lie inside the annular trough of the drive-transmission pulley *e* so as to leave a substantial clearance between the opposed inside faces of said trough when the clutch blocks are in neutral position.

To prevent the endwise tilting of the clutch blocks *s'''* a spring *y* (Figure 3) is secured to the lever arm *s''* in position to resist such tilting by pressing upon the clutch block on opposite sides of the center.

The upper ends of the levers *s''* are curved inwardly to form an engagement with the sliding cone sleeve *t* which is loosely mounted on the driving shaft *o* intermediate of its ends. The levers *s''* preferably have contact rollers *s''''* to form this engagement with the cone sleeve. The lower end of the cone sleeve is tapered or conical so that when the sleeve is raised it will not interfere with the inward movement of the upper ends of the levers *s''* and will, therefore, permit the clutch blocks mounted on the lower ends of said levers to spring outwardly until they form a strong frictional engagement with the inside wall of the flange *e'* of the pulley. The friction blocks *s''''* are preferably provided with some friction lining material *s'''''* on their outer faces to increase the gripping friction against the pulley.

When the cone sleeve *t* is depressed to its lowermost position its lower conical face acts to expand or force apart the upper ends of the levers and thus to retract the clutch blocks from frictional engagement with the pulley acting against centrifugal force.

Any suitable shifting means may be employed to shift the cone sleeve from operative to inoperative position. In this case I

employ a sector arm *u* which is moved up and down by engagement with the worm *u'* on the shaft *u''* which carries an operating hand wheel *u'''* and is mounted in a supporting bracket *u'''*. The sector arm is connected with an annular yoke *t''* having an interior groove fitting over projections *t'* which are preferably provided with anti-friction rollers *t'''*. A brake band *w* may be located around the outside of the pulley for the purpose of more quickly stopping the rotation of the machine after the friction blocks have been disengaged from their frictional driving connection with the pulley.

It will be observed that the plane of engagement between the centrifugal friction blocks *s''''* and the driving pulley *e* is practically on a level with the center of oscillation of the bearing head and the basket shaft where the sidewise motion of the pulley is inappreciable and where no lateral pressure will be exerted against the rotary bearings which support the basket shaft.

It will be observed that with the above described arrangement all parts of the driving connection are rendered very conveniently accessible to the attendant, that there is no interference with the oscillation of the basket shaft by the driving connection, and particularly that the driving connection is not only very direct but is controllable as to starting and stopping.

It will also be understood that while I have shown a driving connection with the line shaft I do not confine myself to such driving means in the application of this invention.

What I claim is:

1. In a centrifugal machine, the combination of a hollow gyratory non-rotating suspension head mounted in a fixed hanger to gyrate about a center intermediate of its ends against a yielding centralizing buffer, a rotary basket shaft extending through said head and rotatably suspended against axial lifting movement in said head, anti-friction radial bearings located at the upper and at the lower ends of said head to rotatively sustain the radial thrust of the basket shaft both above and below the center of gyration, and a driving member secured to said rotary shaft and surrounding the suspension head at the level of the center of gyration whereby the driving power is applied intermediate of said radial bearings at the plane of the center of gyration, and the lifting of the shaft in relation to said head is prevented, substantially as described.

2. In a centrifugal machine, the combination of a hollow gyratory non-rotating suspension head mounted in a fixed hanger to gyrate about a center intermediate of its ends against a yielding centralizing buffer, a suspended rotary basket shaft extending up through said suspension head, anti-fric-

- tion radial bearings located at the upper and at the lower ends of said head to rotatively sustain the radial thrust of the basket shaft both above and below the center of gyration, 5 one of said bearings also acting to sustain the vertical thrust of the basket shaft, and coacting driving clutch elements for rotating said shaft arranged around the outside of said head and having operative engagement 10 at the level of the center of gyration of the centrifugal, substantially as described.
3. In a mount for driving centrifugal machines the combination of a suspended gyroscopic shaft, an oscillatory bearing head provided with upper and lower anti-friction 15 bearings for rotatably engaging and supporting said shaft said bearings being located respectively on opposite sides of the center of oscillation, a friction pulley secured to the upper end of said shaft, driving mechanism embracing a non-oscillatory vertically aligned driving shaft, pivotal arms supported thereby and friction blocks loosely carried by said arms to engage said driving pulley in a horizontal plane intermediate of said upper and lower bearings under the action of centrifugal force, and means for forcing said friction blocks out of engagement 20 with said pulley, substantially as described.
4. The combination of a gyroscopic centrifugal shaft suspended at its upper end on a universal joint support, a driving pulley secured to the upper end of said shaft and extending 25 downwardly below the center of gyration and having an outwardly and upwardly turned flange to form an annular trough portion, an overhead co-axial driving shaft, pivotal arms carried by said driving shaft to rotate therewith, friction blocks loosely connected to the lower ends of said arms and suspended thereby in said annular trough to move outward into frictional engagement with said annular flange under the 30 action of centrifugal force, and means engaging the upper ends of said levers to force them outwardly in order to retract the friction blocks from contact with said pulley, substantially as described.
5. In a driving mount for centrifugal machines, the combination of a rotary basket shaft suspended by a universal joint to gyrate about a fixed center of oscillation 35 against yielding resistance, a friction-drive transmission pulley secured to the upper end 55 of said shaft with its friction-drive surface lying in substantially the horizontal plane of said center of oscillation, an overhead axially aligned driving shaft having a spider secured to its lower end, a plurality of friction clutch blocks movably supported by said spider in the horizontal plane of said center of oscillation to engage the friction surface of said transmission pulley, and means controlled at will for withdrawing and holding 60 said clutch blocks out of driving engagement with said pulley while the machine is rotating, substantially as described.
6. In a driving mount for centrifugal machines, the combination of a rotary gyroscopic basket shaft suspended to swing about a fixed center of oscillation, a hollow oscillatory suspension head having upper and lower bearings on opposite sides of the center of oscillation affording rotary support 65 for said basket shaft, a hollow fixed hanger therefor having a supporting flange below said center of oscillation, a drive-transmission pulley secured to the upper end 70 of said basket shaft and extending down outside said hanger with an annular clutch surface located outside said hanger, and a driving clutch suspended from an overhead shaft with its clutch members opposed to said pulley clutch surface, substantially as 75 described.
7. In a driving mount for centrifugal machines, the combination of a fixed hollow hanger, an oscillatory suspension head mounted therein and having a peripheral 80 centralizing flange engaged with the interior of the hanger to prevent lateral shifting of said suspension head, said suspension head being supported to oscillate against yielding resistance, a rotary basket shaft mounted to 85 rotate in and gyrate with said suspension head, a clutch pulley secured to the upper end of said shaft and a rotary clutch having centrifugal clutch members disposed opposite the clutch surface of said clutch pulley in substantially the plane of the peripheral centralizing flange of the suspension head, substantially as described.

In witness whereof, I have subscribed the above specification.

EUGENE ROBERTS.
